UNITED STATES PATENT OFFICE

GEORGE T. JACOCKS, OF BROOKLYN, NEW YORK, ASSIGNOR, BY MESNE ASSIGNMENTS, TO ALCO PRODUCTS INCORPORATED, OF NEW YORK, N. Y., A CORPORATION OF DELAWARE

HEATING BOILER

Application filed January 27, 1928. Serial No. 249,923.

My invention relates to a heating system and more particularly to a method of constructing hot water or steam boilers. My invention lends itself especially to welded 5 sheet metal construction.

In hot water or steam heating systems there are several disadvantages to existing arrangements and boiler constructions, particularly where attempts have been made in the 10 past to use sheet metal structures.

Existing types of boilers comprise cast iron or other shells spaced apart by numerous bolts, and have banks of pipes disposed horizontally and extending through the fire 15 chamber. This introduces a problem in the operation of the furnace since the pipe surfaces become insulated by reason of the collection of soot and dirt thereon, and also from the accumulation of mud, silt, etc., in- 20 side the pipes and the headers connected thereto. Since the shells are joined at numerous places by bolts, many points are present where leakage can occur to such an extent as to require discontinuing operation of the 25 boiler for repairs and certainly causing an inconvenience to the owner and operator of the boiler. The boilers now constructed as one unit necessitate special building facilities when installing or replacing the boiler.

It is desirable in steam boiler furnaces to effect the maximum transfer of heat to the water confined in the boiler and to the steam, as generated, in order to secure the greatest efficiency of the furnace. This maximum 25 heat transfer can be obtained with sheet metal constructions such as I propose.

It is therefore the principal object of my invention to provide a construction of heating system boiler that will eliminate all of 40 the foregoing difficulties, and have numerous other advantages making to a boiler of the greatest efficiency in operation, simplicity of construction and mobility in assembly and in transportation.

In the structure I propose, the boiler is composed of a plurality of separate units each complete in itself. Each unit consists 45 of a plurality of thin or narrow water pas- sages or columns surrounding a plurality of 50 long narrow flues through which the gases

and hot air pass from the fire box to the flue. Both the water columns and the air flues are vertically disposed and so arranged as to substantially eliminate any area for soot and flue dirt to collect thereon, to thus interfere with 55 the efficiency of operation of the boiler. Any possible collection of dirt from the flue is substantially confined to the top edges of the narrow water columns where the heated gases are spent before entering into the flue and 60 the transfer of heat to the water and steam completed.

The entire unit is formed of sheet metal, that is to say, the air flues and the enclosing walls of each unit are composed of sheets of 65 uniform thickness throughout and are welded together to form the unit construction. The spacers between units are likewise constructed of sheet metal.

By providing relatively thin water col- 70 umns surrounded by relatively thin sheet metal walls, the water and the steam generated therefrom are very quickly and efficiently heated.

The bottom of each of my improved units 75 is constructed with arched walls so that silt and other dirt in the water will not accumulate thereon to insulate the water columns from the heat at the point of greatest heat. My unit is further constructed so that all of 80 this water dirt readily falls to a low point in the unit by the natural wash of the system. The low point is in direct communication with the drain and therefore any accumulation is readily washed out or may be other- 85 wise removed.

The units are so designed that any number thereof may be connected together to form a boiler of any size desired.

There are many structural advantages to 90 the form of boiler as described in the following specification and which will be apparent therefrom. Insofar as these advantages may be obtained with other forms of construction I do not wish to be limited to the specific embodiment shown in the accompanying drawings, wherein—

Figure 1 is a perspective view partly in section and with parts broken away to facil- 100

itate illustration of a portion of a boiler constructed in accordance with my invention;

Fig. 2 is a perspective view of a portion of the fire box roof structure;

5 Fig. 3 is a cross section of my improved furnace taken on line III—III of Fig. 5;

Fig. 4 is also a cross section of my improved furnace taken on line IV—IV of Fig. 6;

10 Fig. 5 is a side view partly in section and partly in elevation, taken on the line V—V of Fig. 3, and

Fig. 6 is a transverse sectional view of my improved boiler, taken on the line VI—VI of Fig. 3.

15 In the structure hereinafter described, I propose to use sheet metal throughout and to weld all parts together. For convenience, I have accentuated the showing of the weld joints so that specific numerical reference 20 need not be made thereto throughout the following specification.

Referring to Figs. 1 and 3 of the drawings, a complete boiler comprises a plurality of units 9, 9a and 9b. Of course, a boiler 25 may have any number of units desired or required. Each unit comprises a pair of concave side plates 12 and 13 that are welded at each end to flanged U-shaped headers 10 and 11. The headers 10 and 11 and plates 12 and 30 13 are vertically disposed and, when closed at top and bottom as hereinafter described, form a water and steam chamber 14. The chamber 14 is divided into a plurality of thin water columns and air passages which are 35 formed by pairs of L-shaped or arcuate sheets 15 and 16 welded together at their ends and forming substantially rectangular passages communicating with the fire box and the flue at their respective ends. A 40 slotted top plate 17 overlies and is secured to the upper edges of the headers 10 and 11 and the side plates 12 and 13, so as to close the chamber 14 and leave the air passages formed by sheets 15 and 16 unobstructed. 45 The sheets 15 and 16 project through the openings in the top plate and are welded thereto as indicated in Fig. 5. The sheets 15 and 16 are maintained apart to form the air passages by compression struts 20. The struts 50 are secured in place by being welded at their outer ends (as shown in Fig. 1, for convenience, and Fig. 2). Each unit is provided with water inlet ports 18 and water or steam outlet ports 19, respectively located at the lower and upper portions of the headers 10 and 11.

55 The bottom of each unit is so formed as to constitute the roof and side walls of the fire box 21. The bottom plate 22 of each unit is slotted for the reception of the lower ends 60 of the sheets 15 and 16 which extend beyond the plate 22 and are welded thereto as clearly shown in Figs. 2 and 6. The plate 22 is arched for purposes hereinafter described, and the bottom of the various sheets and 65 plates conform thereto. The plate 22 is bent

downwardly on each side outside of the area of the air passages, so as to form a portion of the side walls 23 of the fire box 21. (No attempt is made to show a complete fire box as that comprises no part of my invention.) 70 The bottom of each unit is completely sealed by bending the plate 22 outwardly at the base of the fire box and cutting the same so as to conform to the interior of the headers 10 and 11 where it is welded in place, as indicated at 24 in Figs. 1 and 6, to seal the headers at this point.

75 Having described one complete unit, I will now describe how a plurality of these units may be assembled into a boiler of any desired size. As many units as are desired may be built at the factory and shipped to the point of use, or the units may be shipped disassembled and readily assembled at the point of use since the principal operation is that of welding. 80

85 When the several units are constructed and in place, large spaces exist at each side between adjacent headers. These I propose to partially fill with intermediate spacer units 90 25 forming auxiliary water and steam chambers.

95 Each spacer comprises a flanged U-shaped header similar to headers 10 and 11, and a V-shaped plate 26 welded to the flanges of the header, an overlying top plate (not specifically shown) and a bottom plate 27 formed similarly to plate 22 to constitute a portion of the side walls of the fire box, and a portion 100 of the roof thereof, and being bent to fit into the header, the top and bottom plates being welded to the header and V-shaped plate so as to seal the spacer. Two spacers are placed between each two units and the remainder of the area between units is in open 105 communication with the fire box and the flue and forms an additional passage 28 for the hot air and gases. 110

115 The headers of the spacers are provided with inlet and outlet openings corresponding to the openings 18 and 19 in the headers 10 and 11. Between the headers are placed hollow spacing struts 32 in alignment with the openings 18 and 19, and if desired bracing struts 33 may be mounted inside the several 120 headers, in any suitable manner. Tie-rod bolts 34 are passed through the several aligned inlet and outlet openings and also through appropriate coupling connectors 35 to the water and steam supply mains when the furnace is to be assembled in place. By taking up on the nuts on the ends of the bolts 34 the whole structure is brought together preferably until the flanges of the several headers touch. The seam 36 between the flanges (which in these drawings is accentuated for convenience of illustration) 125 may either be caulked or welded to render the same airtight.

130 When the furnace is assembled, the ash

pit lining 37, the grate support 38 and the grate 39 are secured in place, as well as the usual fire box lining, etc., not shown. The lining 37 acts as a support for the lower walls 5 22 of the units.

In the interest of greater efficiency of operation and also the accommodation and jacketing of a fire door, I propose to modify the units that are to be used as the front and 10 back units of my assembled furnace.

Referring to Figs. 3, 4 and 5, I propose to omit the outermost air passages formed by the plates 15 and 16 and also change the external 15 sheets 12 and 13 which normally are of the shape indicated for the sheet 12 in Fig. 1.

Referring to the front unit, the sheet 12 is extended the full height of the furnace from the top plate 17 to the level of the grate 39 with no arched portion such as is shown 20 providing for the roof 22. A fire door frame 40 is inserted in the front panel 12 and welded thereto, an opening just the size of the frame having been previously cut in the panel 12. The door is afterwards mounted on the frame 25 in the usual manner.

The water compartment 14 is now sealed at the bottom and the fire door is provided with a water jacket by the insertion of a sheet 41. At the top the sheet 41 takes the 30 shape of the bottom plate 22 of the unit and is welded thereto, and at its bottom the plate 41 has a flange 41' turned inwardly to form the bottom of the water jacket around the fire door. The fire door frame is welded to 35 the plate 41 and the flange 41' is welded to the sheet 12 as indicated in Fig. 5. At its sides the plate 41 is welded to the side portion 23 of the bottom plate 22 of the unit. Thus, the fire door is provided with a water jacket 40 in direct contact therewith and across the front of the furnace.

For the rear unit the outermost sheet 12 or 45 13 is removed as well as the rearmost air passage and there is substituted for the rearmost sheet 12 a convex sheet which extends from the top plate 17 to the level of the grate.

A plate 44 (Figs. 3 and 4) is spaced from the modified rear wall 12 and extends from the bottom of the fire box to the plate 22, 50 taking the contour of the plate 22 at its top. The plate 44 is formed and mounted the same as heretofore described with reference to plate 41 and the description need not be repeated. Of course, the plate 22 is cut away 55 so as to admit water into the portions enclosed by the plates 41 and 44 so that the fire box is completely surrounded by a water jacket.

When the several units are in place a flue 60 42 is formed on top of the boiler by the rounded sheet 43 which is flanged and welded to the top plates 17 of the units and spacers. The flue connects with the chimney or smoke-stack (not shown) in well known manner.

65 In referring to the drawings, it will be

noted that the chamber 14 is elliptical in cross section, is disposed vertically, and is divided into many thin narrow portions by the vertical air flues which in turn are narrow. Hence the unit comprises a plurality of thin narrow water columns surrounded by passages for the hot air and gases passing from the fire box to the flue. The air passages have spacing members which also act as heat transfer agencies. Likewise, the space between 70 units is also used as an air passage so that the units are likewise surrounded by hot air passages.

Since the columns are vertically disposed, ample room is provided for the generation of 80 steam in the column before it passes out of the boiler to the requirements therefor so that the steam is more thoroughly heated than in structures of the prior art. The heating is uniform throughout because my improved 85 structure contemplates the use throughout of plates of uniform thickness, and the comparative thinness of the walls insures rapid transmission of heat to the water and steam.

It should also be noted that the water is 90 introduced into the boiler immediately adjacent and alongside the fire box and entirely surrounds the same, thus bringing the water in closest practical proximity to the source of heat.

Soot, ashes and chimney dirt can only accumulate on the narrow portions of the top plates 17 where substantially no heat transfer occurs, thus insuring efficiency of operation in this regard. Likewise, any water, dirt or mud will not accumulate on the top of plates 100 22, but will be washed down into the base of the headers where it may be carried away by water passing out of the boiler, or may be removed in any well known manner. This accumulation, if any, is not over the fire box.

A few of the structural features to be noted are the rigidity of the large and spaced sheet structures by reason of their elliptical shape and the welding of the sheets 12, 13, 15 and 16 to top and bottom plates with the unique construction at the bottom where longitudinal welds of considerable length are obtained. Furthermore, the linings 37 afford additional strengthening of the units at the bottom 115 thereof, and the engagement of the long narrow edges of the flanges when the units are drawn together greatly aids the rigidity of the assembling structure. If the flue plate 43 is not put on until after the tightening of the bolts 34, the clamping by the bolts will be 120 "set".

When any portion of the furnace may require replacement, that particular section may be removed and repaired or replaced. Since the welding that is required is of a simple character and along seams which are readily reached, the possibilities of leakage at the joints is very greatly reduced, and by the elimination of the stay bolts, the greatest 125 130

present cause of leakage in existing types of boilers is eliminated.

Modifications may be made in the arrangement and location of parts but such modifications are within the spirit and scope of my invention and are intended to be covered by the appended claims.

I claim:

1. A heating boiler comprising units of spaced, vertically disposed sheets, top and bottom transverse closing members each having a plurality of spaced slots and a plurality of air passages vertically disposed between said spaced sheets, said air passages being spaced relatively to each other each of the air passages leading through one of the slots in the top member and one of the slots in the bottom member, said sheets and walls of said air passages maintaining a continuity throughout the height of the boiler above the firebox.

2. A heating boiler comprising units of spaced, vertically disposed sheets, top and bottom closing members and a plurality of air passages vertically disposed between said spaced sheets, said air passages being spaced relatively to each other, and said bottom closing members being arched to form a recess.

3. A heating boiler comprising a plurality of sheet metal units each consisting of vertically disposed sheets, spaced from one another, top and bottom transverse closing members each having a plurality of spaced slots and a plurality of air passages vertically disposed between said spaced sheets, said air passages being spaced relatively to each other each of the air passages leading through one of the slots in the top member and one of the slots in the bottom member, said sheets and walls of said air passages maintaining a continuity throughout the height of the boiler above the firebox, all of said sheets being welded at the joints thereof.

4. A heating boiler comprising sheet metal units each having vertically disposed sheets arcuately formed with respect to its transverse axis and spaced from one another, top and bottom transverse closing members each having a plurality of spaced slots and a plurality of air passages vertically disposed between said spaced sheets, said air passages being spaced relatively to each other each of the air passages leading through one of the slots in the top member and one of the slots in the bottom member said sheets and walls of said air passages maintaining a continuity throughout the height of the boiler above the firebox, all of said sheets being welded at the joints thereof.

5. A boiler comprising a plurality of units each comprising enclosing front and rear walls and a plurality of substantially parallel vertical walls of sheet metal straight in a vertical direction directed transversely of the boiler to provide vertical straight

edges, said edges being united in pairs by welding to provide a plurality of vertical relatively narrow passages, some of which being adapted for the fluid and others of which being adapted for the passage therethrough of the gases from the boiler fire box, and top and bottom transverse closing plates each formed with a plurality of slots in open communication with the gas passages.

6. In a heating boiler, a plurality of welded sheet metal units comprising vertically disposed sheets, said units being convex relatively to each other through their transverse axis, a plurality of sheet metal enclosed passages disposed between said vertical sheets and substantially parallel thereto, said passages being in spaced relation to each other, top and bottom transverse plates each having a plurality of spaced slots welded to the top and bottom portions of said vertical sheets and said passages so as to form open and closed chambers in said unit, and said bottom plate forming a portion of a fire box.

7. In a heating boiler, a plurality of welded sheet metal units comprising vertically disposed sheets, said units being convex relatively to each other through their transverse axis, a plurality of sheet metal enclosed passages disposed between said vertical sheets and substantially parallel thereto, said passages being in spaced relation to each other, perforate top and bottom plates welded to the top and bottom portions of said vertical sheets and said passages so as to form open and closed chambers in said unit, said bottom plate forming a portion of a fire box, a plurality of spacers interlocking with said units, said spacers comprising vertically disposed chambers.

8. In a heating boiler, a plurality of welded sheet metal units comprising vertically disposed sheets, said units being convex relatively to each other through their transverse axis, a plurality of sheet metal enclosed passages disposed between said vertical sheets and substantially parallel thereto, said passages being in spaced relation to each other, perforate top and bottom plates welded to the top and bottom portions of said vertical sheets and said passages so as to form open and closed chambers in said unit, said bottom plate forming a portion of the boiler fire box, a plurality of intermediate spacers interlocking with said units, said spacers comprising vertically disposed U and V shaped sheet members welded along their abutting edges, top and bottom plates welded thereto, said bottom plate forming another portion of the fire box.

9. In a heating boiler, a plurality of welded sheet metal units comprising vertically disposed sheets, said units being convex relatively to each other through their transverse axis, a plurality of sheet metal enclosed passages disposed between said verti-

cal sheets and substantially parallel thereto, said passages being in spaced relation to each other, perforate top and bottom plates welded to the top and bottom portions of said vertical sheets and said passages so as to form open and closed chambers in said unit, said bottom plate forming a portion of the boiler fire box, a plurality of intermediate spacers interlocking with said units, said spacers comprising vertically disposed **U** and **V** shaped sheet members welded along their abutting edges, top and bottom plates welded thereto, said bottom plate forming another portion of the fire box, a fire door mounted in one of said units, aligned inlet and outlet openings in said units and spacers, and tie rods inserted through the assembly of units and spacers and securing them together.

10. In a heating boiler, a plurality of welded sheet metal units comprising vertically disposed sheets, said units being convex relatively to each other through their transverse axis, a plurality of sheet metal enclosed passages disposed between said vertical sheets and substantially parallel thereto, said passages being in spaced relation to each other, perforate top and bottom plates welded to the top and bottom portions of said vertical sheets and said passages so as to form open and closed chambers in said unit, said bottom plate forming a portion of the boiler fire box, a plurality of intermediate spacers interlocking with said units, said spacers comprising vertically disposed **U** and **V** shaped sheet members welded along their abutting edges, top and bottom plates welded thereto, said bottom plate forming another portion of the fire box, a fire door mounted in one of said units, aligned inlet and outlet openings in said units and spacers, and securing the assembly of units and spacers together.

11. In a heating boiler, a plurality of welded sheet metal units comprising vertically disposed sheets, said units being convex relatively to each other through their transverse axis, a plurality of sheet metal enclosed passages disposed between said vertical sheets and substantially parallel thereto, said passages being in spaced relation to each other, perforate top and bottom plates welded to the top and bottom portions of said vertical sheets and said passages so as to form open and closed chambers in said unit, said bottom plate forming a portion of the boiler fire box, a plurality of intermediate spacers interlocking with said units, said spacers comprising vertically disposed **U** and **V** shaped sheet members welded along their abutting edges, top and bottom plates welded thereto, said bottom plate forming another

portion of the fire box, a fire door mounted in one of said units, aligned inlet and outlet openings in said units and spacers, tubular compression elements disposed between said units and spacers and aligned with said openings, tie rods extending through said openings and tubular elements and clamping means associated with said tie rods, to secure the assembly of units and spacers together.

12. In a heating boiler, a plurality of welded sheet metal units comprising vertically disposed sheets, said units being convex relatively to each other through their transverse axis, a plurality of sheet metal enclosed passages disposed between said vertical sheets and substantially parallel thereto, said passages being in spaced relation to each other, perforate top and bottom plates welded to the top and bottom portions of said vertical sheets and said passages so as to form open and closed chambers in said unit, said bottom plate forming a portion of the boiler fire box, a plurality of intermediate spacers interlocking with said units, said spacers comprising vertically disposed **U** and **V** shaped sheet members welded along their abutting edges, top and bottom plates welded thereto, said bottom plate forming another portion of the fire box, a fire door mounted in one of said units, aligned inlet and outlet openings in said units and spacers, tubular compression elements disposed between said units and spacers and aligned with said openings, tie rods extending through said openings and tubular elements and securing the assembly of units and spacers together, and a flue chamber welded to the aforementioned top plates and horizontally disposed thereacross, to provide a chimney connection.

13. In a vertical boiler, unitary welded sheet metal sections, consisting of **U** shaped end members having convex body members welded thereto, top and bottom plates welded to said end members and convex body members, said convex body members encompassing a plurality of rectangular and arcuate sheets forming passages therethrough and secured by welding to said top and bottom plates, and means for securing a plurality of said unitary sections together.

14. A heating boiler comprising a section formed of a plurality of vertical sheets of metal enclosing the section and also a plurality of air passages therethrough, said sheets and walls of said air passages maintaining a continuity throughout the height of the boiler above the fire box, and bottom and top transverse plates each having a plurality of spaced slots closing the bottom and top of said section except for the air passages, so that said section when completed consists of a plurality of thin or narrow enclosed sections vertically disposed and adapted to re-

ceive a fluid to be heated, and a plurality of air passages in intimate contact with the enclosed passages and also vertically disposed, and leading through the slots in the top and bottom plates.

- 5 15. A heating boiler comprising a section formed of a plurality of vertical sheets of metal enclosing the section and also a plurality of air passages therethrough, said sheets and walls of said air passages maintaining a continuity throughout the height of the boiler above the fire box, and bottom and top transverse plates each having a plurality of spaced slots closing the bottom and top of said section except for the air passages, so that said section when completed consists of a plurality of thin or narrow enclosed sections vertically disposed and adapted to receive a fluid to be heated, a plurality of air passages in intimate contact with the enclosed 10 15 20 25 30 35 40 45 50 55 60 65 70 75 80 85 90 95 100 105 110 115 120 125 130 135 140 145 150 155 160 165 170 175 180 185
